(57) **CLAIM**

We claim the ornamental design for a model vehicle upper suspension arm, as shown and described.

DESCRIPTION

FIG. 1 is an upper, left, front perspective view of a model vehicle upper suspension arm showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is an upper plan view thereof;

FIG. 7 is a bottom plan view thereof;

FIG. 8 is a bottom, right, rear perspective view thereof; and, FIG. 9 is an upper, left, front perspective view of the model vehicle upper suspension arm from a different angle than FIG. 1.

In the drawings, the broken lines illustrate portions of the model vehicle upper suspension arm that form no part of the claimed design.

In the drawings, only the first embodiment of the model vehicle upper suspension arm is shown. The second embodiment of the claimed design is a right model vehicle upper suspension arm which is a mirror image of the left model vehicle upper suspension arm disclosed in the first embodiment.
